METHOD FOR TREATING SURFACES

Louis S. Wertz, Cleveland, Ohio

Application December 18, 1939, Serial No. 309,799

6 Claims. (Cl. 72—127)

This invention relates to a method of and apparatus for treating surfaces and pertains particularly to the treatment of porous surfaces, such as concrete, masonry and other similar surfaces.

It is an object of the present invention to provide a process and apparatus for the treatment of concrete surfaces and the like by which such surfaces are rendered weather-resistant. Ordinary methods of treating concrete and other similar surfaces usually involve coating the surface with a water-repellent material. In my prior Patent 1,766,419, granted June 24, 1930, is disclosed a device for treating concrete and other similar surfaces by working a weatherproofing material into the surfaces by rotary brushes or carborundum stones. While this device operates satisfactorily in the treatment of concrete surfaces, its use is limited in practice to the treatment of relatively flat surfaces. It is furthermore objectionable because of the force required by the operator to maintain it in contact with certain surfaces due to the gyratory effect of the rotating tool.

It is therefore an object of the present invention to provide an apparatus for the treatment of concrete and other similar surfaces which does not require as great an output of force on the part of the operator to maintain it in place.

Another object is to provide an apparatus which may be readily used in the treatment of surfaces having offset portions or other configurations.

A further object is to provide a process and apparatus for the treatment of porous surfaces in which the treating material is caused to penetrate to an appreciable depth into the surface, even greater than the penetration obtained by the device of the above-mentioned patent.

A still further object is to provide a process and apparatus for the treatment of surfaces in which a considerable part of the liquid content of the repair material is dissipated during treatment so that the drying time for the treating material is minimized and the voids of the surface are filled with substantially inert or non-volatile material.

Other objects and advantages of the present invention will become apparent from the following detailed description accompanied by the drawing, in which like parts throughout the several views are indicated by the same reference numerals.

In the drawing:

Figure 1 is an elevational view of apparatus which may be used to carry out the process of the

present invention illustrating how it may be disposed with respect to the surface during treatment thereof:

Fig. 2 is a bottom plan view of the apparatus in Fig. 1 showing one outline which may be given to the member in contact with the surface;

Fig. 3 is a sectional view of the apparatus in Fig. 1 taken substantially on the line 3—3 of Fig. 2;

Fig. 4 is an end elevational view of a modified form of apparatus for use in treating certain surfaces; and

Fig. 5 is a side elevational view of the apparatus shown in Fig. 4 taken substantially on line 5—5 of Fig. 4.

Briefly, the process of the present invention comprises applying a treating material to the surface to be treated and causing the material to penetrate into the surface by impacting the material while on the repair surface. At the same time a considerable part of the liquid content of the material is dissipated. The effect of the treatment is to seal the porosities of the surface by filling them with the treating material and forcing treating material to penetrate into the minute crevices and interstices of the material constituting the surface, as well as covering the surface itself. In this manner the treating material is intimately bonded to the surface and may be said to become a part thereof. Since the voids and porosities of the surface are filled, the surface is rendered impervious and highly resistant to weathering.

Fig. 1 shows apparatus which may be used to carry out the above treatment as it would be positioned against a surface 1 which is to be treated. The surface may be concrete as the surface of a concrete wall structure, or it may be any other surface conforming to the requisite characteristics of having porosities or voids and having sufficient strength to withstand treatment. It is contemplated that the treatment described herein is especially applicable in weatherproofing the surface of concrete, brick, or masonry structures of all kinds.

The apparatus comprises a member 2 having a face 3 complementary to the surface being treated, a feed line or conduit 4 to conduct treating material to the surface 1, and means for impacting the material on the surface 1, indicated generally by A and shown as a conventional air hammer. In the form of apparatus shown in Figs. 1-3, the member 2 is made circular and of a resilient material, such as rubber and may be secured in any suitable manner to an identical sheet 5 of a

more rigid material, such as a rubber containing a large amount of carbon black or the like. The contact member may be made of a resilient material so that by holding it against the surface 1 a better contact and seal between the surface and the apparatus is insured.

The sheet of material 5 is secured in any suitable manner to a body 6 to which the material feed line 4 and the impacting means A may be detachably connected. Fig. 3 shows the line 4 connected to a valve 7 which is in turn threadedly connected to the body 6 in register with an aperture or passage 8 through the body 6 and communicating with the contact face 3 or member 2 by means of the central axial aperture 10 disposed concentrically of the member 2 and the sheet 5. The passage 8 is preferably inclined at an angle through the body 6 so that the impacting means A may be attached approximately centrally of the body 6. A boss 11 is disposed on the side of the body opposite from the member 2 and has provided therein a spherical socket 12 to receive a ball 13 which is attached to one end of a shank 14. The ball 13 is held in the socket 12 by an apertured plate 15 which is disposed around the shank 14 and bolted to the boss 11 by suitable bolts 16. This construction provides a universal joint connection between the shank 14 and the body 6, that is, the shank 14 may be disposed at varied angles to the surface 1 while the member 2 and body 6 remain in contact with the surface 1.

To lighten the apparatus the body 6 may be formed of some light metal or alloy and reinforced by ribs 17. Then when the impacting or vibrating means A is attached to the body 6 by engagement with the shank 14, the apparatus as a whole may be kept sufficiently light that it will not be objectionably heavy to operate.

In operation the apparatus is held against the surface to be treated and the treating material fed from any suitable source (not shown) through the line 4, the passage 8, and the aperture 10 to the surface 1, the amount of material fed to the surface being readily controlled by the valve 7. It is preferable that the treating material be fed under pressure, which need not be great, to insure that an adequate supply is available for the treatment. The impacting or vibrating means A is started into operation and as the treating material flows from the aperture 10 onto the surface 1 it is impacted into the surface by the member 2 and caused to penetrate into the porosities, voids, and interstices of the surface to fill the same and seal the surface. The multiplicity of impacts on the film of treating material subjects the film to momentary high pressures which force the treating material into the voids or pores. Continuation of the impacting forces liquid of the treating material further into the material adjacent the surface, leaving the voids nearer the surface filled with solids and substantially inert or non-volatile materials. By moving the apparatus over the entire surface while maintaining the feed of treating material and the impacting, the voids and porosities of the surface may be filled and the surface rendered impervious and weather resistant to a high degree.

The treating material used may be varied depending on the nature of the surface and the conditions to which it is to be exposed. For example, in the treatment of concrete surfaces on concrete structures such as walls, bridges, dams, etc., it is often desirable to use a material having some strength in itself. An example of

such a material comprises Portland cement; a silicious filler, which may have hydraulic properties in itself, such as the pozzolanas, blast furnace slag, fly ash, acidic colloidal silica, etc.; a plasticizing or lubricating agent, such as oleaginous materials, including fatty acid glycerides, fatty acids, or salts and esters thereof, as well as stabilizing agents and wetting agents, examples of which are alginates, casein, bentonites, gum tragacanth and alkylated sulphonated aromatic compounds or salts thereof; and the proper amount of water to obtain the desired consistency. It is desirable that the amount of water used be only great enough to obtain a mix which may be flowed onto the surface so that the drying time of the material will be a minimum. Such a material as described above is very advantageous because the particles of the dry ingredients are held in a stable suspension so that they may be forced through hose lines without separation and high frictional losses and will penetrate into small voids and interstices. Further, the hydration of the cement is delayed until the material has been impacted into the surface and a considerable amount of the water has been forced out. Thus the water-to-cement ratio is low and the strength of the treating material when set is relatively great.

Where strength of the treating material is not required and relatively high water repellent characteristics are desired, a composition which has been found very advantageous comprises a binding material such as a pitch or bitumen, together with a drying oil, preferably one which is difficultly saponifiable; an inert filler including pulverized clays, fuller's earth, pulverized limestone, and the like; and a compatible thinner such as turpentine, heavy benzine, mineral spirits, etc. This composition has the property of rendering the treated surface highly repellent to water and thus is very advantageous in treating surfaces to prevent water gaining access to the interior of a structure where it may cause disintegration.

Figs. 4 and 5 of the drawing disclose a modification of the apparatus shown in Figs. 1 to 3, which modification is very advantageous for use in the treatment of structures in which the surface to be treated is limited in size. For example, the treatment of mortar joints or the surfaces between adjacent layers of brick or stone is greatly facilitated by such an apparatus. The contact member 2 presents a face 3 which is rectilinear and of a width suitable for reaching a mortar joint disposed between adjacent layers of brick or other masonry. As in the apparatus shown in Figs. 1 to 3, the contact member 2 is preferably resilient and is secured to the sheet 5, which in turn is secured to a similar sheet 18. The sheet 18 is preferably rigid and may be fastened to the body 6 by means of screws 19, as shown in Fig. 5. By this construction the contact member 2 and the sheet 5 secured to the sheet 18 may be readily replaced should they become worn. Also, various sizes and shapes of units which include a contact member may be secured to the sheet 18 and fastened to the body 6.

The feed line 4 is adapted to be connected to the body at the aperture or passageway 8. The passageway 8 communicates with the contact face 3 of the contact member 2 by a passage 21 through the sheets 18 and 5 and through the contact member 2. To facilitate the flow of treating material throughout the face 3 of the

member 2, a groove 20 may be disposed in the face 3 leading from the opening of the passage 21.

The connection between shank 14, to which the impacting means is attached, and the body 6 is also varied in the modification shown in Figs. 4 and 5. In the modification, the shank 14 terminates in a pair of bifurcated ends 22 which are disposed at each side of and pivotally connected to a lug 23 projecting from the body 6. The pivotal connection is obtained by a pin 24, which is journaled in both the lug 23 and the bifurcated ends 22 of the shank 14. The operation of the modified form of apparatus is substantially the same as that of the apparatus shown in that of Figs. 1 to 3.

By having a considerable distance between the passage 21 and between the passage 10 or 21 and the outer extremities of the contact member, advantage is taken of frictional resistance of the film on the surfaces 1 and 3 to obtain an increased maximum pressure for forcing the material into the porous surface. Thus in the operation of the device, the pressure on the film of treating material which is normally maintained over the contact surface is, by the impressed vibration, periodically raised substantially above the pressure of the material in the aperture 10 or 21. The pressure of the contact face 3 against the surface 1 over a considerable area spaced from the material feed passages aids in preventing a flow of material back into the feed passages and high penetration of the material into the porous surface 1 is obtained.

When the structure to be treated is spalled or disintegrated, a modification of the previously described process may be employed to advantage. Any loose material should be removed from the area of the structure to be surfaced. Then a member or form may be disposed adjacent to the structure with its contact face complementary to the surface to be formed. Suitable surfacing material, which will usually be a cement slurry, may be applied to the area of the structure in any suitable manner. For example, the material may be forced through the member or form into the shallow cavity between the irregular surface of the structure and the form. To securely bond the surfacing material to the existing structure the surfacing material may be impacted by a suitable impacting or vibrating means, which may be disposed against the form to transmit the impacts to the material. When the surface cavities of the structure have been sufficiently filled with surfacing material so that such surface is substantially plane, the member or form may be removed and the surfacing material when dried will be securely bonded to the existing structure.

To render the surface of the structure being repaired weatherproof and impervious, the previously described process of applying weatherproofing material and thoroughly impacting it into the surface may be utilized. When this has been done the new surface of the structure will be very dense, and the highly resistant weatherproof coating will be firmly bonded to the structure. This modification of the present invention may be applied to structures having relatively shallow cavities which require repairing.

The finished surface obtained by the present invention has a longer life than surfaces obtained by methods of spraying, trowelling, or brushing a coating onto the surface. Since the pores and voids adjacent the surface are more thoroughly

filled with substantially inert and non-volatile material, deleterious substance cannot remain on the surface or gain access to the structure to cause disintegration.

It may be seen that many other forms of apparatus may be used to carry out the process of the present invention. For example, the surface to be treated may have offset portions or other irregular changes in contour and it is contemplated that such a surface be treated with an apparatus having a contact member whose contact face is complementary with the surface to be treated. Furthermore, the feed of the treating material to the surface undergoing treatment may be accomplished in many other ways than those shown, it merely being necessary that there is sufficient treating material available at the surface to be impacted into such surface.

Also it is contemplated that the impacting means may be one of several well known types. It is believed that it may be advantageous from the standpoint of the operator to use an impacting means which will deliver impacts of relatively high frequency so that intensity of an individual impact may be reduced without decreasing the necessary amount of impacting.

The above described process is very desirable for weatherproofing porous surfaces such as the surface of concrete and other similar structures, because the pores of the surface are filled by a material which is firmly bonded to the surface and is impervious to moisture, fumes, or other deleterious substances. An enduring decorative surface may be obtained which will protect and increase the useful life of the treated surface. To enhance the decorative character of the coating, various colored filling materials may be incorporated into the treating material to give it a pleasing color.

It is to be understood that variations and modifications of the steps of the process and the specific device herein shown and described for purposes of illustration may be made without departing from the spirit of the invention.

What I claim is:

1. The method of weatherproofing concrete and other structures, which comprises presenting a member having a depressible contact face to a surface of such structure, feeding a highly flowable and pumpable weatherproofing material through a central portion of said face to the surface of the structure, imparting a multiplicity of forcible impacts to the member substantially normal to said surface to cause penetration of the material into the pores of the structure, and continuing said impacting and feeding until the surface and adjacent regions are rendered substantially impervious, said material having solid particles in suspension and being pumpable through hose lines and fine passageways without separation of the solids.

2. The method of treating concrete and masonry structures and the like to densify them in the region of their surface, which comprises presenting a member having a resilient depressible face against a surface of such structure, feeding a highly flowable material containing a Portland cement, a pozzolanic material, a lubricating agent, and water through said face into contact with the surface of the structure, said material having particles in sufficiently stable suspension to be pumpable through hose lines and fine passageways without separation and high frictional losses, and repeatedly and forcefully impacting said material on said surface prior to

gelation of the cement in a direction substantially normal to said surface to cause penetration of the material into the pores and fine voids of the structure.

3. The method of treating concrete and masonry structures and the like to densify them in the region of their surface, which comprises presenting a member having a resilient depressible face against a surface of such structure, feeding a highly flowable material containing an hydraulic cement, a finely divided filler containing a substantial amount of acidic colloidal silica to retard gelation, a lubricating agent in an amount up to 2% of the weight of the cement, and water through said face into contact with the surface of the structure, said material having particles in sufficiently stable suspension to be pumpable through hose lines and fine passageways without separation and high frictional losses, and repeatedly and forcefully impacting said material on said surface prior to gelation of the cement in a direction substantially normal to said surface to cause penetration of the material into the pores and fine voids of the structure.

4. The method of weatherproofing concrete and other structures, which comprises presenting a member having a depressible contact face to a surface of such structure, feeding a hardenable flowable pumpable material containing a hydraulic cement, a finely divided filling material having a substantial proportion of acidic colloidal silica, water, and an oleaginous material through said face to the surface of said structures, and imparting a multiplicity of impacts of momentary high pressures to said member and substantially normal to said face to cause

penetration of the material into the pores of the surface and into the region inwardly of said surface of the structures.

5. The method of weatherproofing concrete and other structures, which comprises presenting a member having a depressible contact face to a surface of such structure, feeding a hardenable flowable pumpable material containing a hydraulic cement, a finely divided filling material having a substantial proportion of acidic colloidal silica, water, and a small amount of a fatty acid derivative through said face to the surface of said structures, imparting a multiplicity of impacts of momentary high pressure to said member and substantially normal to said face to cause penetration of the material into the pores of the surface and into the region inwardly of said surface of the structures, and continuing said impacting and said feeding until the surface and the region for a substantial distance inwardly are rendered substantially impervious.

6. The method of weatherproofing concrete and other structures, which comprises presenting a member having a depressible contact face to a surface of said structure, feeding a flowable and pumpable material containing a bitumen, an inert finely divided filling material and a compatible thinner through said face to the surface of said structure, and imparting a multiplicity of impacts of momentary high pressure to said member and substantially normal to said face to cause penetration of the material into the pores of the surface and into the region inwardly of said surface of the structures.
